US00D714290S

(12) **United States Design Patent**
Tanaka et al.

(10) **Patent No.:** **US D714,290 S**
(45) **Date of Patent:** **** Sep. 30, 2014**

(54) **SCANNER**(71) Applicants: **Hiromitsu Tanaka**, Nagoya (JP); **Ai Kishimoto**, Nagoya (JP)(72) Inventors: **Hiromitsu Tanaka**, Nagoya (JP); **Ai Kishimoto**, Nagoya (JP)(73) Assignee: **Brother Industries, Ltd.**, Nagoya (JP)(**) Term: **14 Years**(21) Appl. No.: **29/457,541**(22) Filed: **Jun. 11, 2013**(30) **Foreign Application Priority Data**

Dec. 21, 2012 (JP) 2012-31299

(57) **CLAIM**

The ornamental design for a scanner, as shown and described.

DESCRIPTION

FIG. 1 is a perspective view of a scanner;

FIG. 2 is a front view thereof;

FIG. 3 is a top view thereof;

FIG. 4 is a right-side view thereof;

FIG. 5 is a left-side view thereof;

FIG. 6 is a rear view thereof; and,

FIG. 7 is a bottom view thereof.

Broken lines and unshaded portions contained within broken line are not claimed.

1 Claim, 4 Drawing Sheets(56)
